DRIP CUP FOR AN UMBRELLA OR THE LIKE

Richard H. Davis, 280 Richton, Highland Park, Mich.

Filed Sept. 26, 1960, Ser. No. 62,258

Term of patent 14 years

(Cl. D88—3)

FIG. 1 is a front elevational view of a drip cup for an umbrella or the like, showing my new design;

FIG. 2 is a top plan view;

FIG. 3 is a side elevational view; and

FIG. 4 is a bottom plan view thereof.

The broken line showing of a portion of an umbrella in FIG. 1 is for illustrative purposes only.

I claim:

The ornamental design for a drip cup for an umbrella or the like, as shown and described.
